UNITED STATES PATENT OFFICE.

AURELIAN L. KANE, OF OSSINING, NEW YORK.

SMOKEHOUSE.

1,383,814.

Specification of Letters Patent. Patented July 5, 1921.

Application filed September 14, 1920. Serial No. 410,190.

To all whom it may concern:

Be it known that I, AURELIAN L. KANE, a citizen of the United States, and a resident of Ossining, in the county of Westchester 5 and State of New York, have invented certain new and useful Improvements in Smokehouses, of which the following is a specification.

The invention relates to apparatus for 10 smoking and curing food products, such as sausages, ham, fish and the like; and it has for its object a smoke house or compartment in which the smoking of the products will be effected with a minimum shrinkage 15 of same and with a superior quality resulting therefrom. To this end, the invention consists in providing a housing or casing wherein heating as well as smoking apparatus is provided and in manner such that 20 no cool draft from below the products will be permitted to reach same during the treatment; also, wherein a too rapid cooling of the air is prevented after the drying burners are shut off.

25 The nature of the invention will best be understood when described in connection with the accompanying drawings, in which—

Figure 1 is a vertical section of the im- 30 proved smoke house.

Fig. 2 is a horizontal section thereof taken on the line 2—2, Fig. 1, looking in the direction of the arrows; and Fig. 3 is a detail view of the heat storage portion of the 35 apparatus.

Similar characters of reference designate corresponding parts throughout the several views.

Referring to the drawings, 10 designates 40 a suitable housing or casing in the lower portion of which sawdust or similar material is designed to be supplied through an opening or door 11, said sawdust being ignited by flames from a gas pipe 12 extending over same and having burner openings 13 therein directed toward said sawdust. The sawdust will generate the smoke for curing the food products as in the well-known method of providing the smoke and no claim 45 is made to same *per se*.

Above the opening or door 11 and in the uppermost portion of the housing are mounted suitable shelves or racks 14 for supporting the products (not shown) to be treated, 50 the same being hung thereon in any convenient manner. Between these racks and

the top of the opening 11 is disposed additional gas supply means 15 having suitable burner openings 16 which are designed to provide heat for temporarily drying the 60 food products.

In order to prevent too great a fluctuation of heat of the drying chamber after this gas supply means is shut off, as well as to prevent actual contact of cool air drafts with 65 the food products, which air may enter during the smoking operation when the door 11 is opened to introduce an additional supply of sawdust, heat retaining means in the nature of series of baffles 17 are mounted over 70 the pipes or gas supplying means 15 and the flames therefrom directed against same. In this manner, any cool air entering through the door 11 must first pass through the baffle plates 17 and be thereby warmed, 75 it being understood that the lower burners 13 are used especially for the burning of sawdust to produce the smoke for curing. The heat retainers may be of standard fire brick and are designed to accumulate the 80 heat as well as to baffle the flames which are directed thereto, so that no direct flame will strike food products to be hung above same.

In operation, I have found that it is well 85 to first heat the smoke house by means of the burners 16, for example, from 100° to 145° F., during which time considerable heat will be accumulated by the fire brick. The food products are then run into the smoke 90 house after first being air dried as much as possible and are allowed to remain at the above temperature in the smoke house until thoroughly dried. Thereupon, the lower burners 13 are lighted to ignite the saw- 95 dust on the floor of the fire pit and the desired smoke produced. The burners 16 are then either turned off entirely, or gradually, to allow the temperature to gradually drop to 110° F. which temperature is maintained, 100 substantially, during the smoking process. The fire brick during this period acts to maintain a more or less uniform temperature and prevent any sudden fluctuation, it being understood, of course, that some heat 105 will also be supplied by the lower burners 13. In this manner, a satisfactory control of temperature is possible, excessive shrinkages being avoided and superior products obtained.

I claim:

1. In apparatus of the character described:

- the combination with a housing; of means for supporting, in the upper portion thereof, products to be smoked, said housing being adapted to contain smoke producing material in the lower portion thereof; gas supply means to ignite said smoke producing material; additional gas supply means above the said door; and heat retaining material above said additional gas supply means and below the support for said products.
- 5 2. In apparatus of the character described: the combination with a housing; of means for supporting, in the upper portion thereof, products to be smoked, and a door below same, said housing being adapted to contain smoke producing material in the lower portion thereof; gas supply means to ignite said
- 10 15

smoke producing material; additional gas supply means above the said door; and heat retaining material above said additional gas supply means and below the support for said products.

3. In apparatus of the character set forth: the combination with a housing; of means for burning therein smoke producing material; heat producing means beyond the said burning means; and heat retaining means associated with said heat producing means and through which the smoke produced may pass.

Signed at New York, in the county of New York and State of New York, this 9th day of September, A. D. 1920.

AURELIAN L. KANE.
